Warren E. Willis.
ATTORNEY

UNITED STATES PATENT OFFICE.

LEONARD H. HARDING, OF BROOKLYN, NEW YORK.

LIQUID-LEVEL CONTROL.

Application filed September 21, 1926. Serial No. 136,782.

This invention relates to float actuated devices for the control of electrically operated apparatus, such for instance as producing an audible signal at a point remote from a tank or sump, or to govern the action of electrically driven pumps regulating the height of liquid in the tank.

It is one of the objects of the present invention to provide a weighted float movable 10 on a guide rod within certain adjustable limits, thereafter causing the rod to raise or lower, the rod in turn operating a switch whereby an electrical current is controlled.

A further feature is in the provision of 15 means adjustable on the rod and operative in a sealed casing, whereby a snap switch is positively actuated into either of its operative positions, avoiding the possibility of a partial or incomplete action.

Another aim is to enclose the rod, switch 20 and actuating devices in such manner as to prevent it from being molested or tampered with.

These and other minor advantages, which 25 will become more fully evident as the description proceeds, are accomplished by the construction, arrangement and combination of the few and simple parts hereinafter described and illustrated in the accompanying 30 drawing, forming a material part of this disclosure, and in which:—

Figure 1 is a general side elevational view of an embodiment of the invention as installed.

Figure 2 is an enlarged vertical sectional view of the upper part of the structure as assembled.

In the drawing, the numeral 5 designates 40 in general a conventional type of tank, such for instance as is frequently used for fire protection on top of buildings, but which may also represent a well or sump from which it is required to draw off a portion of its liquid contents when the same has reached a predetermined level.

Above the main portion of the tank or sump is a chamber 11 divided usually by a flooring or partition 12, the liquid 13 obviously being in the lower portion of the 50 tank.

Fixed on the flooring 12 is the flange of a 55 collar 14 having a set screw to adjustably retain a tube 15, passing through the flooring any desired distance into the tank and having fixed at its upper end a casing com-

prised of two opposed like parts 16 and 17, their flanged meeting edges having between them a gasket 18 held tightly by the clamping screws 19.

Passing vertically through the casing side 60 16 is a rod 20 loosely surrounded by the guard tube 15 and extending into the tank 10.

Adjustably fixed on the lower portion of the rod are collars 21 and 22, respectively 65 upper and lower, and between the collars is a tube 23 forming the axis of a spherical float 24 in which the tube is hermetically sealed.

The float rests on the liquid 13 and may be 70 weighted as at 25 to enter a suitable distance into the liquid, the float and its tube being freely slidable on the rod 20.

The upper portion of the rod is slidably 75 guided in the upper and lower walls of the casing through lubricated stuffing boxes 36 and 37, respectively upper and lower, set in the casing 16 and fixedly attached to the rod is a spool 26 having annular flanges at its ends the lower normally resting on a spacer sleeve 27 seated on the lower wall of the 80 casing; a similar spacer sleeve 28 encircling the rod above the spool limiting its rise.

Fixed in the casing 17 is any one of the well known standard makes of snap switches 29 85 operated by a lever 30 disposed between the spool flanges, this type of switch snapping from one position to the other when the lever is moved past the center of its oscillation, having no "dead center" or neutral position, being positive at all times.

Attached to the outer side of the casing 17, containing the switch, is a junction box 31 having a cover 32 through which extend a lead-in wire 33 and outlet wires respectively 34 and 35 encased in insulation colored so as 90 to be readily distinguished.

In operation let it be assumed that the liquid in the tank has reached a stage requiring replenishing, as indicated by the views, the weighted float resting on the collar 22, drawing the rod to its lowermost position and, by reason of the spool 26 engaging the switch lever 30, throwing the switch so that current may be conducted to a motor driven supply pump, not shown, a signal, or both as 100 may be preferred.

The pump upon being started, either direct by an electric current or a watchman receiving a lower water signal, will begin to refill 105 the tank, causing the float 24 to rise and upon

- contact of the float with the upper collar 21, indicating the high water level, will raise the rod 20 and sleeve, carrying the switch lever 30 past its center whereupon it will snap into the position shown in broken lines in Figure 2, throwing the switch into an opposite position, thereby giving a high water signal, the sleeve 28 limiting the rise of the rod and spool.
- 10 Obviously the operations may be reversed in the case of a well or sump from which liquid must be withdrawn when a certain level has been reached.
- It is further intended to provide a sealed covering for the casing and outlet box so that the apparatus having been properly adjusted cannot be tampered with injudiciously or maliciously, rendering the device essentially fool proof.
- 15 As the operative parts are extremely simple, if a proper switch be used and adjustments be correctly made the device may be depended upon to operate indefinitely and without lubrication, care or supervision.
- 20 Although the foregoing is descriptive of the preferred embodiment of the invention, it will be apparent that minor changes may be made in its construction, without the exercise of invention or conflicting with the scope 25 of the claims hereto appended.
- Having thus described my invention, what I claim as new and desire to secure by Letters Patent, is:—
1. A liquid level control device comprising a casing, a height adjustable tube sup-
- porting the casing, a rod passing through said casing and tube packings in said casing for the tube, a snap switch in said casing, said switch having an oscillatable control lever, a flanged spool on said rod engaging said lever, 40 adjustable stops on the lower exposed portion of said rod, a sleeve slidable on said rod to engage said stops and a float fixed intermediate the length of said sleeve.
2. A float controlled electric switch comprising a sectional casing composed of two equal portions united at their flanged edges and having a gasket interposed therebetween, a junction box on the exterior of one section, a snap switch fixed in said section, said switch having an operating lever extending into the other section, a tubular guard tube fixed in said casing, an adjustable support collar for said tube whereby said casing may be raised and lowered, a rod slidable through the last named casing section, said rod being partially enclosed in said tube packings in said casing for said rod, a double flanged spool fixed on said rod within the last named section to engage the switch lever, means in said casing to limit the movement of said spool in either direction, a weighted float movable on the extending portion of said rod and stops adjustable on said rod to control the movement of said float relative thereto.
- 60 Signed at New York, in the county of New York and State of New York, this 16th day of September, A. D. 1926.
